UNITED STATES PATENT OFFICE.

ALEXANDER MONROE CRAIG, OF WESTPORT, CANADA.

TRACE-COUPING.

SPECIFICATION forming part of Letters Patent No. 681,443, dated August 27, 1901.

Application filed April 26, 1901. Serial No. 57,534. (No model.)

To all whom it may concern:

Be it known that I, ALEXANDER MONROE CRAIG, a subject of the King of Great Britain, residing at Westport, in the county of Leeds, 5 in the Province of Ontario, in the Dominion of Canada, have invented certain new and useful Improvements in Trace-Couplings, of which the following is a specification.

My invention has for its object to lengthen 10 and shorten a trace by a coupling having one member secured to the hame-tug and the other member to the trace, the latter to slide against the former, and a spring-catch to hold the members at the adjusted position to 15 suit a proper length for the trace.

My invention consists in the construction, arrangement, and combination of parts comprising the coupling, as hereinafter claimed.

Figure 1 is an elevation of the exterior face 20 of the trace and hame-tug coupled as in use, a portion of one thickness of the trace broken away to expose the trace member of the coupling, the tug intact and connected to the hame. Fig. 2 is a like view of the opposite 25 face of Fig. 1, a portion of the tug-strap broken away to show a portion of the tug member of the coupling and one thickness of the trace broken away to show in elevation one end of the trace member of the coupling.

Fig. 3 is a longitudinal section of Figs. 1 and 30 2 intact. Fig. 4 is a cross-section on line xx , Fig. 3. Fig. 5 is a plan of the outer face of the tug member of the coupling detached, omitting the spring-catch. Fig. 6 is a longitudinal section of the spring-catch detached. Fig. 7 is an end elevation of said catch, a top 35 view of which is seen in Fig. 2. Fig. 8 is a plan of the inner face of the trace member of the coupling detached. Fig. 9 is a longitudinal 40 section of Fig. 8. Fig. 10 is a cross-section of Fig. 8 on line yy , and Fig. 11 is a plan of the inner thickness of the trace to show slots to admit passage of the head of the spring-catch and the slots to receive the 45 slides of the trace member of the coupling.

1 represents a metallic plate or strip or the 50 tug member of the coupling, and it has extending from one end a finger 2, flattened on one side, to which the hame-tug strap 3 is riveted through holes 2^a in the finger. The strap passes through a tug-loop 4 on the hame 5, and the other end of said strap is secured

to plate 1 by a rivet 6 near the end oppositely to the finger, the strap thereby covering the plate for nearly its full length to keep it from 55 contact with the horse, and plate 1 has longitudinally parallel V-shaped slideway-slots 7.

10 is the sliding or extension trace member of the coupling, said member being a straight bar, preferably half-oval in cross-section and 60 flattened at the ends and provided near one end with dovetail slide-lugs 11, which slide in said way-slots 7 and guide the movable member or bar 10 when adjusting the coupling to lengthen or shorten a trace, and said 65 bar 10 has a plurality of longitudinal indentations 18, each having at one end a resistance-stud 19.

20 is a spring-catch fitting into an aperture 8 near one end of plate 1, and said catch has 70 a flat spring 24, which is secured to said plate by the rivet 6 and is provided with a thumb piece or portion 21 to lift the catch by hand against the resistance of the spring to uncouple. The head of the spring-catch 20 75 passes through slots 15 of the one thickness 13 of the trace, said slots being to allow the head of the spring-catch to descend into and engage one of the series of indentations 18, whereby the catch will resist the pull of the 80 draft by holding the plate and bar coupled.

The bar 10 is preferably covered by another thickness of leather 17, which is stitched to the other thickness of leather 13 to make the trace complete. Hence bar 10 when in use is 85 not seen.

9 is a tongueless buckle or loop on the free end of plate 1, and the trace for convenience passes through said buckle, which has a passage-way sufficiently deep to receive a girth- 90 strap 22 transversely to the trace, and said buckle is provided with a stud 23 to enter a hole in the girth to support the trace.

I claim as my invention—

1. The combination with a trace and hame 95 tug strap of a harness, of a coupling-plate secured to said strap and having longitudinal slideway-slots, a spring-catch carried by said plate, a coupling-bar secured to the trace and having lugs sliding in said slots and longitudinal indentations engaged by said catch to hold the plate and bar coupled, substantially as set forth.

2. A trace-coupling, comprising a coup-

ling-plate 1, having a finger attachable to a hame-tug strap 3, by rivets and having longitudinal slideway-slots 7, a spring-catch fitting an aperture in said plate, and a coupling-bar 10, having indentations 15 engaged by said spring-catch, to keep said plate and bar coupled at an adjusted sliding position, and having lugs 11, sliding in said slots when the catch is released and the bar pulled or pushed to lengthen and shorten a trace, substantially as set forth.

3. A trace extension-coupling consisting of a coupling-plate attachable to a hame-tug strap and having longitudinal slideway-slots, a coupling-bar attachable to a trace and hav-

ing lugs sliding in said slots whereby said plate and bar have a sliding connection, said bar provided with longitudinal indentations, and a spring-catch carried by said plate and engaging said indentations to hold the bar at an adjustment to suit the length of trace desired, and to resist the pull of the draft, substantially as set forth.

In testimony whereof I have signed my name to this specification in the presence of two subscribing witnesses.

ALEXANDER MONROE CRAIG.
